(57) **CLAIM**

The ornamental design for an auxiliary handle for a liquid container, as shown and described.

DESCRIPTION

FIG. 1 is a perspective view of an auxiliary handle for liquid containers showing one embodiment of my new design;

FIG. 2 is a top view thereof;

FIG. 3 is a front elevational view thereof;

FIG. 4 is a side elevational view thereof, the opposite side being a mirror image thereof;

FIG. 5 is a rear elevational view thereof;

FIG. 6 is a perspective view of a slightly different modification of the embodiment shown in FIG. 1;

FIG. 7 is a top view thereof;

FIG. 8 is a front elevational view thereof;

FIG. 9 is a side elevational view thereof, the opposite side being a mirror image thereof; and,

FIG. 10 is a rear elevational view thereof.

The broken lines are for illustrative purposes only and form no part of the claimed design.
